UNITED STATES PATENT OFFICE.

SIDNEY J. EVERETT, OF NEW YORK, N. Y., ASSIGNOR, BY MESNE ASSIGNMENTS, TO THE FISHKILL MANUFACTURING COMPANY, OF SAME PLACE.

FOLDING BOX.

SPECIFICATION forming part of Letters Patent No. 276,676, dated May 1, 1883.

Application filed July 1, 1882. Renewed March 27, 1883. (No model.)

To all whom it may concern:

Be it known that I, SIDNEY J. EVERETT, of the city of New York, State of New York, have invented certain new and useful improvements in that class of boxes known as "Folding" or "Knockdown" Boxes, of which the following is a specification.

In the accompanying drawings, Figure 1 is a blank of thick paper, or card-board, or similar material, cut and creased and ready to be folded into a box, with the string, tape, ribbon, or similar material attached. Figs. 2, 3, 4, and 6 are end views of different styles of my box when closed and ready for use; and Fig. 5 is a side view of a box also closed and ready for use.

Similar letters of reference designate corresponding parts in all figures.

These boxes are made from thick paper, or card-board, or similar material, and cut into a blank of the proper size for a box. The boxes vary in size, and the blank must be cut to correspond to the size of the box to be made. The usefulness of such boxes depends largely upon the mode of opening or closing them and the means by which they are held closed when in use. Heretofore such devices have been employed to close them as to render the boxes unsafe to carry with a weight inside. For instance, a slot is used in one of the end laps and a hook or catch in the other end lap to enter the slot and catch and lock upon the side of the slot. Such a device was readily torn away and the contents would fall out. Folding boxes and envelopes have also been made with tapes or cords as a means of securing them when closed, which cords or tapes have been sometimes secured to an end flap or passed through eyelets made for that purpose. More particular references to such devices are found in the patents to Bolchini, August 12, 1879, No. 218,479; Schultz, September 23, 1879, No. 219,879; Buckingham, May 17, 1881, No. 241,525, and Woolhiser, March 21, 1882, No. 255,374; but my invention differs from all these in many respects—as, for instance, none of my flaps are cut round or bevelled or with slits or tongues, and the tape or cord used by me passes through openings in the flap, and is a continuous piece, not two pieces, as

in the Patent No. 255,374, nor does it pass into slits in the side of the flap, as in Patent No. 241,525; and my box differs from these, also, in its construction as to gluing the small flap T onto the side flap, U, and thus the leverage for the cord or tape is more exact, and greater weight can be carried than in other devices, such as have been referred to. By my method this danger is avoided. Again, the boxes heretofore used were often destroyed by the person closing them by tearing the slot or the catch, and in such cases the boxes were worthless, and in all cases the boxes heretofore used could only be used once, because by closing and opening them the end lap would be bent, the material cracked or broken, and thereafter the usefulness of the boxes destroyed. I have overcome all these difficulties, and in addition increase the rapidity by which these knock-down boxes can be set up, filled, and closed, thereby enabling the salesman to wait upon a larger number of customers in the same given time; and I also decrease largely the expense of this class of boxes by my construction, which is a very important item, as they are usually given to the customer with the article purchased.

The blank for my box is cut in six places, A A A, in straight cuts, and it is creased or scored at B B B B and B' B'. These creases allow of the portions marked C D E F G being bent or folded over to close the ends of the box, and the parts at H H to fold up and form the sides of the box. I make small incisions, large enough to pass a cord, string, tape, ribbon, or similar material through. This cord or ribbon I glue fast to the inside of one of the end flaps and pass it through these incisions I J K L M and out over the side of the box, then through the incisions N O P Q R and fasten the other end of the ribbon to the inside of the flap G, and this ribbon S serves for several purposes. It is a handle by which to carry the box, and it pulls the flaps D and E and F and G on either end of the box together and holds them firmly closed when the box is in use. Along one of the edges, as at T, I put glue, then fold this edge over and inside of the opposite edge, U, and press the two edges firmly together. During this operation the creases

or scores B B B B allow the parts to fold, as just described. When the glue has hardened the box is ready for use. At one end the flaps C C are first folded down, then the string or 5 ribbon is pulled through the incisions K L M in the direction of K to M, which closes the flaps D and E. The article is put into the box at the other end, the two flaps C C on that end folded down, the ribbon or string pulled 10 through the incisions P O N in the direction of P to N, and the box is securely closed. The heavier the article inside the tighter the end flaps, D, E, F, and G, are pulled together, and thus the box is more secure, and tightly closed; 15 but the natural weight of the box is of itself sufficient to keep the ends closed, and even if the box be laid down the end flaps, D E F G C C, will not open or fall down. Thus, it will be seen, to open the box and remove its contents 20 the flap D or G is pulled down, and with it the ribbon or string is pulled through the incisions, and then the other two end flaps, C C, are pulled out and the box is open.

The end flaps, C C, are not essential to my 25 box, except as they may be required for special purposes; but the flaps D, E, F, and G, with the ribbon or string, will answer the entire purpose of closing the end of the box.

I have shown in Figs. 2, 3, 4, and 6 modifications of the plan shown in Fig. 1. Thus in 30 Figs. 2 and 4 the incisions J K P Q are omitted, thereby bringing the ribbon or tape outside of the contiguous edges of the flaps D E F G and greatly decreasing the liability of the edges 35 of the flaps to be bent up or torn while in use. The same results and additional strength are obtained and a neater and more attractive end secured by the designs shown in Figs. 3 and 6. In these designs the incisions J, K, P, 40 and Q are omitted, and the incisions L and O are lengthened, so as to receive the tongue-shaped ends of the flaps D and G, as well as the string or tape. In all these modifications there are usually six incisions in the blank— 45 namely, I, L, M, N, O, and R—and the path of the ribbon would be from the interior of the box, at I, out through the incision I and into the interior of the box, again through the incision L and out through the top of the box 50 at the incision M, thence through the incision N to the interior of the box and out of the incision O, and then again to the interior of the

box through the incision R. Should the incisions I and R be omitted, the result would be the same; but in that case the ends of the 55 ribbon would not pass into the interior of the box, but be secured to the outside of the flaps D and G. I prefer, for neatness, to employ these two incisions I and R and secure the ribbon to the inside of the flaps. 60

It will be readily seen that it is the same principle, whether the ribbon or string passes over the edge of the flap or through an incision a little back of the edge. The leverage is made over one of the end flaps, and this holds 65 the other flap tightly closed, and, then passing on the inside of the box, another purchase or point of leverage is obtained, thus dividing the strain on the ribbon and on the box. It is immaterial to which of the end flaps the 70 ribbon is attached, the only difference being that the box will hang as the ribbon passes through one or the other of the sides of the box. Usually two sides of the box are wider than the other two; but the box may be perfectly square, or any other form desired. 75

Having described my invention, what I claim as new is—

1. Two flaps in a knockdown box, provided with a ribbon glued to the inside of one of 80 said flaps, and an incision through said flap, whereby the ribbon passes through the same and over the outside edges of both of said flaps to an incision in the second flap, and through the said incision to the inside of said second 85 flap, and an incision through the top side of the box to permit of the ribbon passing through from the inside of the box, whereby the flaps may be firmly held in place to close the end of the box, and the ribbon used as a handle to 90 carry the box and as a means of holding said flap firmly closed, substantially as described.

2. A folding box provided with one continuous ribbon or cord, glued at its ends to two flaps of said box, and passing through incisions 95 to the interior of the box, and thence out through the top of said box, whereby the box is brought into shape by pulling the ribbon or cord through the incisions, and provided with a handle, substantially as described.
